INVENTOR

ATTORNEYS

UNITED STATES PATENT OFFICE.

JOHN HEARNE, OF NEW YORK, N. Y.

DESIGN FOR A GAS-METER-DIAPHRAGM HOOP.

SPECIFICATION forming part of Design No. 30,029, dated January 17, 1899.

Application filed December 21, 1898. Serial No. 699,969. Term of patent 7 years.

To all whom it may concern:

Be it known that I, JOHN HEARNE, a citizen of the United States, residing at the city of New York, borough of Brooklyn, in the county of Kings and State of New York, have invented and produced a new and original Design for a Gas-Meter-Diaphragm Hoop, of which the following is a specification, reference being had to the accompanying drawings, forming a part thereof, in which—

Figure 1 is a plan view of a gas-meter-diaphragm hoop embodying the features of my design, and Fig. 2 is a side elevation of the same.

The leading features of the design consist in the arched opening A in an edge of the

hoop and the arched flange B appearing upon the inner face of the hoop, the arched flange following the contour of said opening.

A minor feature of the design consists in a bead a at the upper edge of the hoop above the opening A, and an outwardly-extending flange b at the edge of the hoop in which the said opening A is made.

I claim—

The design for a gas-meter-diaphragm hoop herein shown and described.

JOHN HEARNE.
